UNITED STATES PATENT OFFICE.

WILLIAM R. AITKEN, OF HOPKINS, MINNESOTA.

AUTOMATIC CONVEYER.

Application filed October 16, 1926. Serial No. 142,653.

This invention aims to provide novel means for conveying material, and to provide novel means whereby the intake end of the conveying mechanism may be advanced 5 into a pile of material, whilst part of the material is being carried away by the conveying mechanism.

It is within the province of the disclosure to improve generally and to enhance the 10 utility of devices of that type to which the invention appertains.

With the above and other objects in view which will appear as the description proceeds, the invention resides in the combination 15 and arrangement of parts and in the details of construction hereinafter described and claimed, it being understood that changes in the precise embodiment of the invention herein disclosed may be made with- 20 in the scope of what is claimed, without departing from the spirit of the invention.

In the accompanying drawings:—

Figure 1 shows in side elevation, a device constructed in accordance with the invention, parts being broken away;

Figure 2 is a top plan;

Figure 3 is a vertical longitudinal section wherein parts are broken away;

Figure 4 is a fragmental horizontal sec- 30 tion taken on the line 4—4 of Figure 1;

Figure 5 is a transverse section on the line 5—5 of Figure 1;

Figure 6 is a transverse section on the line 6—6 of Figure 1;

Figure 7 is a transverse section on the line 35 7—7 of Figure 1;

Figure 8 is a transverse section on the line 8—8 of Figure 1.

The machine forming the subject matter 40 of this application comprises a fixed support which is denoted generally by the numeral 1. The support 1 is trough-shaped in cross section as disclosed in Figures 7, 8 and 6. The support 1 is provided at its upper edges with outwardly flared wings 2. A table 3 extends longitudinally of the support 1 and is located within the support. Main tracks 4 are mounted on the side walls of the trough-shaped support 1 and are dis- 45 posed above the table 3. Upper tracks 5 are mounted on the table 3 at the edges thereof. Lower tracks 6 are mounted on the sides of the support 1 and are located below the table 3.

The numeral 7 marks a downwardly and forwardly inclined chute which is located at

the rear of the support 1. The chute 7 is provided at its upper edges with outwardly flared wings 8. As shown at 9 in Figure 3, the forward portions of the wings 8 of the chute 7 overlap upon the rear portions of the wings 2 of the support 1. The side walls of the chute 7 may be connected to the corresponding parts of the support 1 by attaching elements 19, and the lower portion of the forward end of the chute 7 may be connected to the lower portion of the rear end of the support 1 in any suitable way, as indicated at 20. At its rear end, the chute 7 has bearing brackets 10 carrying hook-shaped hangers 11 adapted to be engaged with the bearings 12 of a corn sheller or other instrumentality, a drive shaft 14 being journaled in the bearings 12. Although the machine may be used to handle material of various kinds, 75 it will be assumed, to avoid needless repetition, that corn is the material to be handled. The chute 7 has a longitudinal table 15, corresponding to the table 3 of the support 1. The table 15 may be joined to the table 3 80 as indicated at 16. Upper tracks 17 are mounted on the table 15 at the sides of the chute and lower tracks 18 are mounted on the side walls of the chute at some distance below the table 15.

A forward shaft 21 is journaled for rotation in adjustable bearings 22 carried by the support 1 near to the forward end of the support, as Figure 1 will best disclose. Sprocket wheels 23 are mounted on the forward shaft 21, within the support 1, as shown in Figure 3. A rear shaft 24 is journaled in the support 1 near to the back end of the support. The rear shaft 24 carries sprocket wheels 25. Guides 26 are mounted on the side 95 portions of the support 1 near to the rear end thereof. A shaft 27 is mounted to rotate in the bearing brackets 10 of the chute 7. There are sprocket wheels 28 on the shaft 27, the sprocket wheels 28 being located within the chute 7, as Figure 3 will show.

A chain conveyer 29 is engaged around the sprocket wheels 23 on the forward shaft 21, the upper and lower runs of the chain conveyer 29 cooperating with each of the 105 wheels 25 on the shaft 24, and the chain conveyer being engaged around the sprocket wheels 28 on the shaft 27. The chains of the conveyer 29 carry wheels 30 adapted to roll along the upper tracks 5 of the support 1, 110 along the upper tracks 17 of the chute 7, along the lower tracks 18 of the chute 7, and

along the lower tracks 6 of the support 1. The chains of the conveyer 29 are connected by scraper plates 31 which move along the table 3 of the support 1, along the part 16 5 shown in Figure 3, and along the table 15 of the chute 7. As seen in Figure 2, there is a sprocket wheel 32 on the shaft 27, the sprocket wheel 32 being connected by a sprocket chain 33 with a sprocket wheel 34 10 on the drive shaft 14.

The machine comprises a trough-shaped conveyer truck 35, disposed above the support 1 and mounted for longitudinal reciprocation on the support. The conveyer truck 35 has 15 a downwardly and forwardly inclined end 36, both the truck and its end 36 having flared wings 37, the extreme forward corners of the wings 37 being outwardly extended as shown at 38, thereby to receive the material the more 20 readily, as the conveyer truck 35 is moved forwardly on the support 1. Near to its rear 25 end, the conveyer truck 35 is supplied with depending bearings 39 wherein is journaled a shaft 40 carrying wheels 41 adapted to roll 30 along the main tracks 4 of the support 1. The downwardly and forwardly inclined end 36 of the conveyer truck 35 carries bearings 42 wherein is journaled a shaft 43 provided with 35 wheels 44 adapted to roll along the floor 45 of the building wherein the device is employed, although any suitable means may be 40 provided therewith the wheels 44 cooperate. In any event, the wheels 44 and 41 support the 45 conveyer truck 35 for longitudinal movement 50 with respect to the fixed support 1. Located 55 within the conveyer truck 35 is a table 46, part of which slants downwardly to correspond with the slope of the part 36 of the conveyer truck. Upper tracks 47 are mounted on the 60 table 46. Lower tracks 48 are carried by the side portions of the conveyer truck 35 and are disposed below the table 46.

A forward shaft 49 is journaled for rotation in the downwardly and forwardly inclined end 36 of the conveyer truck 35. There are sprocket wheels 50 on the shaft 49. A rear shaft 51 is journaled on the rear part of the conveyer truck 35. There are sprocket wheels 52 on the rear shaft 51. A chain conveyer 55 53 is engaged about the sprocket wheels 52 and 50. The chains of the conveyer 53 are supplied with wheels 54 which move along the upper tracks 47 and along the lower tracks 48. The chains of the conveyer 53 are connected by scraper plates 54 which move along the table 46.

There are sprocket wheels on the ends of the shaft 49, the sprocket wheels being designated by the numeral 56 and being engaged 60 by sprocket chains 57 which are engaged with sprocket wheels 58 on a shaft 59 mounted to rotate in the inclined end 36 of the conveyer truck 35. The sprocket wheels 56, the chains 57 and the sprocket wheels 58 are inclosed 65 within casings 60 which are carried by the

part 36 of the conveyer truck 35. On the shaft 59 is located a rotary feeder, made up of a hub 61 and projecting spokes 62.

There are sprocket wheels 63 on the shaft 24. Sprocket wheels 64 are mounted on the shaft 27. The sprocket wheels 63 and 64 are engaged by sprocket chains 65. A sprocket wheel 66 is mounted on the shaft 24. A sprocket wheel 67 is carried by the shaft 51. An idler 68 is journaled on the side of the conveyer truck 37 at a point slightly in front of the sprocket wheel 67. There is a sprocket wheel 69 on the shaft 21. A sprocket chain 70 is engaged about the sprocket wheel 69, about the sprocket wheel 67, and about the sprocket wheel 66, the upper run of the sprocket chain 70 passing beneath the idler 68.

An eccentric 71 is mounted on the shaft 24. The eccentric 71 cooperates with a strap 72 on an operating rod 73 having a lateral finger 74 that is adjustable in a guide slot 75 formed in a radius arm 76 mounted to swing on a shaft 77, journaled in the support 1. The operating rod 73 reciprocates in a guide 93 pivoted to a link 94 which, in its turn, is pivoted in a bell crank lever 95 which is fulcrumed at 96 on a segment 97 carried by a frame 99 on the side of the support 1, the bell crank lever 95 being supplied with a latch mechanism 98 adapted to cooperate with the segment 97.

A pawl 78 is pivoted to the radius arm 76 and is provided with an eye 79 adapted to be engaged, under circumstances which will be pointed out hereinafter, with a hook 80 or other latch mounted on the radius arm 76. A ratchet wheel 81 is fixed to the shaft 77. There are drums 82 on the shaft 77, outwardly of the support 1, as Figures 6 and 2 will show. Idlers 83 are journaled on the sides 105 of the support 1 near to the forward end of the support. Flexible elements 84 are wound about the drums 82 and are looped around the idlers 83. The flexible elements 84 are crossed upon themselves as at 85, and the ends of the flexible elements 84 are anchored as shown at 86, upon the conveyer truck 35, at spaced points on the conveyer truck.

Noting Figures 4 and 7 especially, it will be seen that a sprocket wheel 87 is mounted 115 on the shaft 77, the sprocket wheel being engaged by a sprocket chain 88 which is engaged with a sprocket wheel 89 rotatable on the shaft 24 but adapted to be connected with the said shaft, to turn therewith, through the instrumentality of a clutch 90 which is splined upon the shaft 24, the clutch being operated by a lever 91 which is fulcrumed on a bracket 92 carried by one side of a support 1.

There are four main operations in connection with the working of the machine and those operations are, the driving of the conveyer 53 and 29; the advancing of the conveyer truck 35 to keep the rotary feeder 61-62 always engaged with the pile of mate- 130

rial; the adjustment at the will of an operator, of the speed at which the conveyer truck 35 and the feeder 61-62 are advanced into the material; and the returning of the conveyer truck 35 to the position depicted in Figure 3, after the conveyer truck has been advanced to the limit.

Relative to the driving of the conveyers, it may be stated that the shaft 14 turns the sprocket wheel 34, the sprocket chain 33 operating the sprocket wheel 32 and rotating the shaft 27, the sprocket wheels 28 imparting movement to the conveyer 29. When the shaft 27 is rotated, the sprocket wheels 64 operate the chains 65 and drive the sprocket wheels 63, rotation thus being imparted to the shaft 24. When the shaft 24 is rotated, the sprocket wheels 25 thereon aid in actuating the conveyer 29. When the shaft 24 is rotated, the sprocket wheel 66 thereon drives the chain 70, the chain 70 turning the sprocket wheel 69, and rotation thus being imparted to the forward shaft 21. The sprocket wheels 23 on the shaft 21 aid in operating the conveyer 29. The chain 70, cooperating with the sprocket wheel 67, rotates the shaft 51 and the sprocket wheels 52 actuate the chain conveyer 53. The chain conveyer 53 turns the shaft 49 by way of the sprocket wheel 50, and the sprocket wheels 56 on the shaft 49 operate the chains 57, the chains driving the sprocket wheels 58 and rotation being imparted to the shaft 59 and to the feeder 61-62.

35 The next operation to be considered is the advancing of the conveyer truck 35 to thrust the rotary feeder 61-62 into the pile of corn or other material. In this connection, it may be stated that the drive shaft 14 operates the sprocket wheel 34, the sprocket chain 33 driving the sprocket wheel 32, and rotation being imparted to the shaft 27. The sprocket wheels 64 and the chains 65 rotate the sprocket wheels 63, rotation being imparted to the shaft 24. The eccentric 71 on the shaft 24 cooperates with the strap 72 and the rod 73 to cause the radius arm 76 to swing on the shaft 77, the finger 14 of the rod 73 being located in the slot 75 of the radius arm 76. 50 When the radius arm 76 is caused to swing as aforesaid, the pawl 78 on the radius arm 76, cooperating with the ratchet wheel 81 on the shaft 77, will impart rotation to the shaft 77, the drums 82 on the shaft 77 moving the flexible elements 84 endwise, the conveyer truck 35 thus being advanced, because the flexible elements 84 are anchored at 86 to the conveyer truck 35.

55 The speed with which the conveyer truck 35 is advanced may be regulated at the will of an operator. This is done by swinging the lever 95, the link 94 raising or lowering the guide 93, the forward end of the rod 73 being raised or lowered, the finger 74 on the rod being shifted, accordingly, in the slot 75

of the radius arm 76, thereby to vary the effective length of the radius arm and to change the throw of the pawl 78 with respect to the ratchet wheel 81, the movement of the drums 82 and the flexible elements 84 being adjusted accordingly. 70

Relative to retracting the conveyer truck 35, the pawl 78 is disengaged from the ratchet wheel 81 and is held out of engagement with the ratchet wheel by hooking the latch 80 into the eye 79 on the pawl 78. The lever 91 is operated to cause the clutch 90 to couple the sprocket wheel 89 to the shaft 24, and, when the shaft 24 is rotated, in the way hereinbefore pointed out, the chain 88, coating with the sprocket wheel 87, will rotate the shaft 77, the drums 82 cooperating with the flexible elements 84 to draw back the conveyer truck 35 into the position shown in Figure 1. 85

So far as the general operation of the machine is concerned, the feeder 61-62 agitates the material and the chain conveyer 53 carries the material backwardly and deposits it on the chain conveyer 29, the chain conveyer 29, in its turn, carrying the material backwardly out of the machine. The conveyer truck 35 and the conveyer 53 are shifted bodily forward, for the purpose specified, and as the conveyer truck 35 moves forwardly, the corn or other material is still deposited by the conveyer 52 on the conveyer 29. 95

What is claimed is:—

1. In a device of the class described, a support, a first conveyer movable on the support, a conveyer truck movable on the support, a second conveyer movable on the truck and discharging on the first conveyer, a shaft supported for rotation, means for connecting the shaft operatively with the truck, to move the truck with respect to the material to be conveyed, and mechanism for actuating the shaft, said mechanism comprising a ratchet wheel on the shaft, a radius arm mounted for swinging movement, a pawl on the radius arm, and cooperating with the ratchet wheel, and means for operating the radius arm. 100

2. In a device of the class described, a support, a first conveyer movable on the support, a conveyer truck movable on the support, a second conveyer movable on the truck and discharging on the first conveyer, a shaft supported for rotation, means for connecting the shaft operatively with the truck, to move the truck with respect to the material to be conveyed, and mechanism for actuating the shaft, said mechanism embodying a radius arm mounted for swinging movement, means for imparting movement from the radius arm to the shaft, an operating rod, means for actuating the operating rod, a shiftable connection between the rod and the radius arm, and means for shifting the connection along the radius arm to vary the effective length of the radius arm. 115

3. In a device of the class described, a support, a first conveyer movable on the support, a conveyer truck movable on the support, a second conveyer movable on the truck and discharging on the first conveyer, a shaft supported for rotation, mechanism for actuating the shaft, and means for connecting the shaft operatively with the truck to move the truck with respect to the material to be conveyed, said means comprising a flexible element wound in its intermediate portion about the shaft, and means for anchoring the ends of the flexible element to the truck.

4. In a device of the class described, a support, a first conveyer movable on the support, a conveyer truck movable on the support, a second conveyer movable on the truck and discharging on the first conveyer, a shaft supported for rotation, means for connecting the shaft operatively with the truck, to move the truck with respect to the material to be conveyed, and mechanism for actuating the shaft, said mechanism embodying a radius arm mounted for swinging movement, a pawl and ratchet connection between the radius arm and the shaft, an eccentric supported for rotation, means for rotating the eccentric, an operating member having a strap engaging the eccentric, a shiftable connection between the operating member and the radius arm, and means under the control of an operator for shifting the connection along the radius arm.

5. In a device of the class described, a support, a first conveyer movable on the support, a conveyer truck movable longitudinally of the support, a second conveyer movable on the truck and discharging on the first conveyer, a first and a second shaft supported for rotation, a flexible element engaged in its intermediate portion about the first shaft and connected at its ends to the conveyer truck, a radius arm mounted for swinging movement, a pawl on the radius arm, a ratchet wheel on the first shaft and coacting with the pawl, an eccentric on the second shaft, an operating member having a strap cooperating with the eccentric, a connection between the operating member and the radius arm, and a driving connection between the shafts, said driving

connection including a clutch whereby the driving connection may be rendered inoperative.

6. In a device of the class described, a support, a first conveyer movable on the support, a conveyer truck movable longitudinally of the support, a second conveyer movable on the truck and discharging on the first conveyer, a first and a second shaft supported for rotation, a flexible element engaged in its intermediate portion about the first shaft and connected at its ends to the conveyer truck, a radius arm mounted for swinging movement, a pawl on the radius arm, a ratchet wheel on the first shaft and coacting with the pawl, an eccentric on the second shaft, an operating member having a strap cooperating with the eccentric, a connection between the operating member and the radius arm, and a driving connection between the shafts, said driving connection including a clutch whereby the driving connection may be rendered inoperative, and means under the control of an operator and engaging the operating member to shift the first-specified connection along the radius arm.

7. In a device of the class described, a support, a first conveyer movable on the support, a conveyer truck movable on the support, a second conveyer movable on the truck and discharging on the first conveyer, a rotatable member, means for connecting the rotatable member operatively with the truck to move the truck with respect to the material to be conveyed, and mechanism for actuating the rotatable member, said mechanism embodying a radius arm mounted for swinging movement, an operating rod, means for driving the operating rod, a shiftable connection between the operating rod and the radius arm, a slide wherein the operating rod reciprocates, a lever under the control of an operator, means for holding the lever in adjusted positions, and means for mounting the slide on the lever, the lever constituting means whereby the shiftable connection may be moved along the radius arm.

In testimony that I claim the foregoing as my own, I have hereto affixed my signature.

WILLIAM R. AITKEN.
